UNITED STATES PATENT OFFICE.

EDWIN N. LIGHTFOOT, OF NEW YORK, N. Y., AND ALVA T. SMITH, OF NEWARK, NEW JERSEY, ASSIGNORS TO THE CUTLER-HAMMER MFG. CO., OF MILWAUKEE, WISCONSIN, A CORPORATION OF WISCONSIN.

ELECTRIC HEATER.

Application filed September 24, 1929. Serial No. 412,459.

To all whom it may concern:

Be it known that we, EDWIN N. LIGHTFOOT and ALVA T. SMITH, citizens of the United States, residing, respectively, at New York, in the county of Bronx and State of New York, and Newark, in the county of Essex and State of New Jersey, have invented new and useful Improvements in Electric Heaters, of which the following is a specification.

This invention relates to an electric heater.

The electric heater, to which the invention particularly applies, comprises in general a resistor associated with a reflector.

An object of the invention is to provide an improved electric heater.

Another object is to provide a simple, durable electric heater of pleasing appearance and at a low cost.

Another object is to increase the heat radiating qualities.

Other objects and advantages will herein-after appear.

In the drawings, which illustrate an embodiment of the invention,

Figure 1 is a front elevation of an electric heater with part of the guard wires removed;

Fig. 2 is a vertical section on line 2—2 of Fig. 1;

Fig. 3 is an enlarged vertical section through the resistor and terminal support and cover therefor;

Fig. 4 is a rear elevation of the terminals and support therefor, the protective cover being shown in section;

Fig. 5 is a front elevation, partly in section of the resistor and its support;

Fig. 6 is a vertical section on line 6—6 of Fig. 2; and

Fig. 7 is a section on line 7—7 of Fig. 1.

The electric heater comprises a reflector bowl 1, a supporting base 2 therefor and a resistor 3 arranged within the bowl and protected by a cage 4.

The reflector bowl 1 is formed of suitable material having a polished inner surface for reflecting the heat rays.

A plurality of raised radial ribs 5 joined at inner and outer ends by similar ribs 6 and

7 respectively are formed in the bowl 1. These ribs are formed by pressing the same from the bowl and may extend either inwardly or outwardly therefrom.

55

The ribs stiffen the bowl, thereby allowing the use of thinner material for the bowl. Other means may, of course, be employed for stiffening the bowl. For example, small depressions instead of ribs may be formed 60 in the bowl.

The ribs also serve to reflect heat and light at various angles from the reflector. For example, the ribs cause the heat developed in the resistor to be reflected through 65 a wide angle, so that the heat will be radiated to objects or persons at a considerable distance to one side or the other of the heater.

Light is reflected by the ribs through a 70 wide angle, and the radiating ribs appear as rays of light, thus improving the appearance of the reflector. To persons at a considerable distance to either side of the heater, the heater appears as a brilliant or glowing 75 object, thus relieving the deadness of the usual heater of this character.

The reflector bowl 1 has an outwardly extending octagonal flange 8, so formed by bending the sections 9 thereof at an angle 80 of 90° thereto. These rearwardly extending sections or flanges 9 brace and stiffen the reflector and its flange 8.

The ribbed reflector bowl with its outwardly extending flange and rearwardly extending stiffening sections may be readily manufactured. A reflector thus formed may be made of thinner material than when no stiffening or rearwardly extending flanges are provided, and the necessary rigidity 85 is secured.

The front face of the outwardly extending flange 8 may be provided with a plurality of ornamental lugs 10 suitably fastened thereto, as by welding or brazing.

95

A handle 11 fastened to the two upper rearwardly extending flanges 9 by rivets or other suitable means, provides ready means for moving the electric heater.

The reflector is adjustably mounted on 100 the base 2 by a hinged connection. This hinged connection includes a bracket 12 se-

cured to the two lower rearwardly extending flanges 9 by rivets or other suitable means, and a standard 13 secured to the base 2 by a screw or other suitable means. The 5 bracket 12 is pivotally connected to the standard 13 by a pivot pin 14.

The resistor 3 formed into a helix is seated in a helical groove provided on the periphery of a tubular insulating support 15. 10 The support 15 is fastened to an insulating base 16 by a bolt or other suitable means.

The insulating base 16 is positioned in a central opening in the reflector bowl 1 and is fastened thereto by means of a clamping 15 ring 17 and screws 18. Other means may, of course, be employed for fastening the insulating base to the reflector bowl.

The tubular resistor support 15 is positioned at the centre of the base 16 which is 20 held in the centrally disposed opening in the reflector. Thus the helical resistor is coiled about an axis which is the axis of the reflector.

Two L-shaped brackets 19 forming terminals for the electric heater are mounted 25 in the insulating base 16 and are fastened thereto by clamping eyelets 20.

The ends of the resistor are straightened and are extended through the interior of 30 the tubular support 15 to openings near the inner end thereof. The ends of the resistor then extend through the eyelets 20 and are connected to the terminals 19 by suitable fastening screws 21.

A cover 22 for the terminals 19 is provided with a central opening through which conductors connected with a source of current supply may extend for connection to the terminals 19, each of which has for this 40 purpose another fastening screw 21.

The opening in the cover 22 is provided with an insulating bushing 23 held therein by a clamping ring 24 seated in a groove in the bushing.

45 The protective cage 4 comprises a plurality of arched guard wires 25 fastened at their diverging ends to a flat ring 26 and at their converging ends to a hub 27. The hub 27 is provided with radial openings 50 through which the converging ends of the guard wires 25 extend into an annular groove 28. The converging ends of the guard wires 25 are held in the hub 27, by solder with 55 which the annular groove 28 is filled after the ends of the guard wires are arranged therein. Other means may, of course, be employed to fasten the guard wires to the hub.

60 The protective cage 4 may be fastened to the reflector by means of rivets or other suitable means extending through the flat 65 ing 26 and the outwardly extending 1 age 8.

The invention contained herein is, of course, susceptible of other embodiments 65 and adaptations.

The invention claimed is:

1. A self sustained reflector for electric heaters and the like, comprising a bowl having an outwardly extending peripheral flange and stiffening flanges projecting rearwardly from said peripheral flange, said stiffening flanges having means for direct pivotal securing of the reflector to a suitable base. 75

10 2. A self sustained reflector for electric heaters and the like, comprising a bowl having stiffening ribs, an outwardly extending flat peripheral flange and additional stiffening flanges projecting rearwardly from said peripheral flange, and a bracket secured to certain of said stiffening flanges to provide for pivotal mounting of said reflector upon a suitable base. 80

15 3. An electric heater comprising a base, a reflector bowl having an external flange at the rim thereof, stiffening flanges extending rearwardly from the periphery of the external flange, a resistor positioned in spaced relation to the reflector bowl, and a bracket rigidly fastened to two of the rearwardly extending flanges and pivotally connected to the base. 85

20 4. An electric heater comprising a base, a reflector bowl having an external flange at the rim thereof, stiffening flanges extending rearwardly from the periphery of the external flange, a resistor positioned in spaced relation to the reflector bowl, a bracket rigidly fastened to two of the rearwardly 90

extending flanges at the bottom of the reflector bowl and pivotally connected to the base, and a handle fastened to two of the rearwardly extending flanges at the top of the reflector bowl. 100

25 5. An electric heater comprising a reflector having a central opening, an insulating plate secured to the back of said reflector circumferentially of said opening and having an integral part penetrating the latter, a heater element base and circuit terminals secured directly to opposite sides of said plate to extend respectively upon opposite sides of said reflector and a protective cover for said terminals. 110

30 6. A reflector for an electric heater comprising a bowl having radially extending heat and light reflecting ribs formed therein, an outwardly extending flange at the rim of the bowl, and a plurality of rearwardly extending stiffening flanges for the outwardly extending flange. 120

In witness whereof, we have hereunto subscribed our names.

EDWIN N. LIGHTFOOT.
ALVA T. SMITH.
